ENGINE STARTER

William L. McGrath, Elmira, N. Y., assignor to
 Eclipse Machine Company, Elmira, N. Y., a
 Corporation of New York

Application October 29, 1926. Serial No. 418,266

25 Claims. (Cl. 74--7)

My invention relates to an engine starter adapted to start an engine such as an internal combustion engine and to that part of an engine starter known as the drive or transmission. The object of my invention is to provide a simple, efficient and reliable drive of novel construction and mode of operation and of that type which is semi-automatic, that is one in which the driving member or pinion is brought into engagement with a member of the engine to be started such as the flywheel by manually operated means, and disengaged therefrom automatically when the engine starts on its own power. Moreover the construction of my drive is such that in the event of failure 15 of the manually operated means to work the driving member may be automatically engaged with the engine member.

In the drawings Fig. 1 is an end elevation of an engine starter embodying my invention with the outer end of the casing broken away; Fig. 2 a sectional elevation thereof; Fig. 3 a section of a modified form of construction of drive; and Fig. 4 a section of another modified form.

For the sake of a clear and definite description 25 of my invention I have selected the particular embodiment thereof as illustrated in the drawings without intention of limitation thereto. Moreover while I have shown the single reduction and outboard type of drive it will be understood that 30 my invention is equally applicable to the double reduction and also inboard type of drive.

As herein shown the prime mover which is here 35 an electric motor 1 has an extended armature shaft 2 on which the drive or transmission is mounted and by which it is rotated. The driving head 3 is secured to the armature shaft 2 by the stud 4. A hollow screw shaft 5 is mounted on the armature shaft and provided with a driven head 6 at its inner end and with a stop nut 7 at its outer 40 end. The two heads 3 and 6 are operatively connected by a yielding driving connection which is here a torsion drive spring 8 anchored at its opposite ends respectively to the stud 4 and to the stud 9.

45 The driving member is here in the form of a pinion 10 having teeth adapted to mesh with the teeth of the engine to be started such as the teeth 11 of the engine flywheel 12. This pinion has a smooth central bore by which it is loosely mounted 50 on the screw threads of the screw shaft with the result that it has freedom of movement both rotarily and longitudinally along substantially the entire length of the screw shaft. This pinion is provided at its inner end with a contact or bearing 55 face formed by a ring or flange 13 which may be

made separate or integral therewith but preferably separate for facility in manufacture.

The control or screw member is a nut 14 threaded upon the screw shaft and provided at one end with a flange 15 forming a complementary contact or bearing surface to the flange 13. The flange 13 is of greater diameter than the flange 15 with the result that an annular portion of the flange 13 projects beyond the flange 15 thereby providing a portion for the cooperation of the 60 manually operated means therewith as herein-after described.

The pinion and nut are wholly disconnected and physically independent of each other and such pinion is held in normal position by a yielding means such as the coiled spring 16 encircling the screw shaft and bearing at one end against the enlarged head 17 of the stop nut and at its other end against the pinion. As shown the spring fits over the body portion of the stop nut 75 so that when the pinion is in contact with such a stop nut the spring will be in compressed condition substantially within the compass of the stop nut.

Describing the manually operated means, such 80 means and the drive are arranged within a casing 18 which is secured by the studs 19 to the motor frame. This casing has a bearing 20 for the outer end of the armature shaft and also supports 21, 22 for the opposite ends of a stationary shaft 23 which is parallel to the armature shaft. A sleeve 24 is mounted to slide on the shaft 23 and the same carries a shifter device 25 which includes yoke arms 26 depending therefrom and terminating in inwardly projecting 85 rounded portions or rollers 27 which are arranged to contact the projecting annular portion of the flange 13. A shifter sleeve 28 is mounted to slide on the sleeve 24 and is held yieldingly to its end position at the right by a coiled spring 29. A second shifter device 30 including yoke arms 31 and inturned rounded portions or rollers 32 is provided to cooperate with the sleeve 28. This yoke 30 is secured to a rock 90 shaft 33 mounted in a bracket 34 on the top of the casing and operatively connected by means of the arm 35 with the manually operated vertical plunger 36. This plunger is normally held upwardly pressed by the coiled spring 37. The plunger carries an adjustable screw 38 in whose 95 path of movement is interposed the button 39 of the electric switch 40 of the motor.

Describing a cycle of operation and starting with the parts in their normal position shown in Fig. 1, the first downward movement of the

plunger rocks the shaft 33 and moves the sleeve 28 to the left thereby carrying with it yieldingly the sleeve 24 and shifter device 25 and also moving the pinion 10 bodily to the left and into mesh with the flywheel. As soon as the pinion has been meshed with the flywheel the switch 40 will be operated by the plunger and the armature shaft will be rotated, with the result that the nut 14 will be automatically advanced forwardly to the left and into clamping contact with the pinion, whereupon such pinion will be drivingly connected with the screw shaft. After the engine starts on its own power and the operator has released the manually operated means, the nut 14 will be automatically retracted to its normal position and the spring 16 will move the pinion out of mesh and to its normal position.

In the event that the pinion teeth and flywheel teeth should abut end to end the construction is such in the manually operated means that the downward movement of the plunger may continue without danger of breaking or jamming of any of the parts. This result is obtained by the yielding operating connection between the sleeves 28 and 24 provided by the spring 29. When under this abutting condition the screw shaft rotates, the nut 14 will be automatically advanced longitudinally and into contact with the pinion which will thereupon rotate slightly angularly so as to come into mesh with the flywheel.

In Fig. 3 I have shown a modified form of construction according to which the screw shaft has a screw threaded portion 41 on which the nut is threaded and a plain portion here formed by a separate bushing 42 on which the pinion slides thereby providing a substantial support for the pinion throughout its length during the driving operation. Otherwise the construction is the same and the operation the same as above set forth.

If according to the modification of Fig. 4, the screw shaft 43 has a plain portion 44 with a stop nut 7 at its outer end. A two diameter collar 46 encircles such portion with its larger diameter overhanging the light coiled spring 47 interposed between it and the nut, and with its smaller diameter entering the outer portion of the pinion bore. When the pinion is shifted longitudinally along the shaft against the spring pressure, the collar will likewise be shifted until the outer end of the collar contacts and is arrested by the stop nut. In other respects the operation is the same.

It will be understood that the plunger may be operated either by hand or foot and therefore when in the claims I refer to manual operation it will be understood that pedal operation is also within the meaning and scope thereof.

I claim:—

1. An engine starter apparatus including a shaft, a driving member mounted on the shaft for longitudinal movement thereon, manually operated means for shifting such driving member longitudinally of the shaft and into engagement with a member of the engine to be started, and means which is adapted to be driven by said shaft and which is movable in one direction relatively to the driving member and by the final movement of which in the same direction the driving relation between said means and driving member is established.

2. An engine starter apparatus including a prime mover, a shaft rotated thereby, a driving member mounted on the shaft for longitudinal

movement thereon, manually operated means for shifting such driving member longitudinally of the shaft and into engagement with a member of the engine to be started, and means which is adapted to be driven by said shaft and which is arranged on the shaft rearwardly of the driving member and which is movable relatively to such driving member, by the final movement of which means the driving relation between said means and the driving member is established.

3. An engine starter apparatus including a prime mover, a shaft rotated thereby, a driving member mounted on the shaft for longitudinal movement thereon, manually operated means for shifting such driving member longitudinally of the shaft and into engagement with a member of the engine to be started, and means which is adapted to act upon the driving member for causing it to be operatively connected with the shaft, and which permits the prime mover to have a running start, such latter means comprising a member mounted on the shaft for automatic longitudinal travel along the shaft when the latter is rotated.

4. An engine starter apparatus including an electric motor, a shaft rotated thereby, a driving member mounted on the shaft for longitudinal movement thereof, manually operated means for shifting such driving member longitudinally of the shaft and into engagement with a member of the engine to be started, and an actuating member mounted on the shaft for automatic longitudinal movement thereon when the motor is operated to thereupon act upon the driving member for drivingly connecting it with the shaft and so mounted as to permit the electric motor to have a running start.

5. An engine starter drive including a rotatable screw-shaft, a driving member mounted on the shaft for longitudinal movement thereon, a screw member threaded on the shaft for automatic longitudinal movement against the driving member as an incident to the rotation of the shaft, and manually operated means for shifting the driving member longitudinally of the shaft and into engagement with a member of the engine to be started.

6. An engine starter drive including a rotatable screw shaft, a driving member mounted on the shaft for longitudinal movement thereon, a screw member threaded on the shaft for automatic longitudinal movement against the driving member as an incident to the rotation of the shaft and manually operated means for shifting its driving member longitudinally of the shaft and into engagement with a member of the engine to be started, said means including a yielding connection.

7. An engine starter drive including a rotatable screw-shaft, a driving member mounted on the shaft for longitudinal movement thereon, a screw member threaded on the shaft for automatic longitudinal movement against the driving member as an incident to the rotation of the shaft and manually operated means for shifting the driving member longitudinally of the shaft and into engagement with a member of the engine to be started said means including a longitudinally movable yoke adapted to loosely contact the driving member for moving the latter only in the direction for engagement with the engine member.

8. An engine starter drive including a rotatable screw-shaft, a driving member mounted on the shaft for longitudinal movement thereon, a screw

- member threaded on the shaft for automatic longitudinal movement against the driving member as an incident to the rotation of the shaft, and manually operated means for shifting the driving member longitudinally of the shaft and into engagement with a member of the engine to be started, said means comprising a yoke mounted to move longitudinally and to engage the driving member to shift it longitudinally, a sleeve, a spring between the sleeve and yoke, and manual means for shifting the sleeve.
9. An engine starter drive including a rotatable screw shaft, a driving member loosely mounted on the shaft for free longitudinal movement thereon, a screw member threaded on the shaft for automatic longitudinal movement against the driving member as an incident to the rotation of the shaft, and manually operated means for shifting the driving member longitudinally of the shaft and into engagement with a member of the engine to be started, said means comprising a stationary shaft parallel to said rotatable shaft, a yoke having a sleeve mounted to slide longitudinally on said stationary shaft, and also having yoke arms adapted to contact said driving member, an actuating sleeve mounted to slide on the yoke sleeve, a spring between the two sleeves, and a manual device for shifting the actuating sleeve.
10. An engine starter drive including a rotatable screw-shaft, a driving member loosely mounted on the shaft for free longitudinal movement thereon, a screw member threaded on the shaft for automatic longitudinal movement against the driving member as an incident to the rotation of the shaft, and manually operated means for shifting the driving member longitudinally of the shaft and into engagement with a member of the engine to be started, said means including a longitudinally movable yoke adapted to loosely contact the driving member for moving the latter only in the direction for engagement with the engine member said driving member having a flange with which the yoke contacts in said movement longitudinally on the shaft.
11. An engine starter drive including a rotatable screw shaft, a driving member loosely mounted on the shaft for free longitudinal movement thereon, a screw member threaded on the shaft for automatic longitudinal movement against the driving member as an incident to the rotation of the shaft, and manually operated means for shifting the driving member longitudinally of the shaft and into engagement with a member of the engine to be started, said two members having cooperating flanges and the flange of the driving member projecting beyond the flange of the screw member, and manually operated means acting on said projecting portion of the driving member flange for shifting the driving member longitudinally of the shaft and into engagement with a member of the engine to be started.
12. An engine starter drive including a screw shaft, a pinion mounted loosely thereon for free longitudinal movement and adapted to engage a member of the engine to be started, a screw member threaded on the shaft for automatic longitudinal movement and adapted to engage the pinion when in engagement with the engine member and thereby operatively connect the pinion and shaft, and manually operated means for shifting the pinion longitudinally into engagement with the engine member.
13. An engine starter drive including a rotatable screw shaft a driving member loosely mounted on the shaft for free longitudinal movement thereon,
- a screw member threaded on the shaft for automatic longitudinal movement against the driving member as an incident to the rotation of the shaft, manually operated means for shifting the driving member longitudinally of the shaft and into engagement with a member of the engine to be started, and means for shifting the driving member longitudinally in the opposite direction after the engine has started on its own power.
14. An engine starter drive including a rotatable screw shaft, a driving member loosely mounted on the shaft for free longitudinal movement thereon, a screw member threaded on the shaft for automatic longitudinal movement against the driving member as an incident to the rotation of the shaft, manually operated means for shifting the driving member longitudinally of the shaft and into engagement with a member of the engine to be started and a spring for shifting the driving member longitudinally in the opposite direction after the engine has started on its own power.
15. An engine starter drive including, in combination with a starting motor and its electrical switch and with a member of the engine to be started, a driving member adapted to be shifted to engage and drive said engine member but normally disengaged therefrom, manual means for so shifting the driving member, means for actuating said switch for rotating the motor prior to full engagement between said members, and operating connections located between the motor and driving member and constructed and arranged to permit such prior rotation of the motor, which rotation causes to be established the driving connection between the driving member and said connections.
16. An engine starter apparatus including a shaft, a driving member mounted on the shaft for longitudinal movement thereon, manually operated means for shifting such driving member longitudinally of the shaft and into engagement with a member of the engine to be started, an actuating member mounted upon and driven by the shaft and having a movement longitudinally on the shaft, which movement is independent of the movement of said driving member, and which movement establishes driving relation between the driving member and shaft, and a friction clutch between the driving member and the actuating member.
17. An engine starter apparatus including a shaft, a driving member mounted on the shaft for longitudinal movement thereon, manually operated means for shifting such driving member longitudinally of the shaft and into engagement with a member of the engine to be started, an actuating member mounted upon and driven by the shaft and having a movement longitudinally on the shaft, which movement is independent of the movement of said driving member, and which movement establishes driving relation between the driving member and shaft, and a friction clutch located between the driving member and the actuating member and arranged to be automatically released when the engine member becomes the driver.
18. An engine starter apparatus including a screw shaft, a pinion mounted on the shaft for longitudinal movement thereon, manually operated means for shifting such pinion longitudinally of the shaft and into engagement with a member of the engine to be started, a screw member threaded on the screw shaft and driven

thereby, and a friction clutch between the pinion and the screw member.

19. An engine starter apparatus including a shaft, a driving member mounted on the shaft for longitudinal movement thereon, and adapted to be driven thereby, manually operated means for shifting such driving member longitudinally of the shaft, and means mounted on said shaft for longitudinal movement thereon to contact the driving member, and also mounted on said shaft for rotary movement therewith after contact with the driving member.

20. An engine starter apparatus including a shaft, a driving member mounted on the shaft for longitudinal movement thereon, and adapted to be driven thereby, manually operated means for shifting such driving member longitudinally of the shaft, and means mounted on said shaft for automatic longitudinal movement thereon to contact the driving member by reason of relative rotation between them and also mounted on said shaft for rotary movement therewith after contact with the driving member.

21. An engine starter apparatus including a shaft, a driving member movable longitudinally thereon for engagement with a member of the engine to be started, manually operated means for moving such driving member longitudinally into such engagement, and means separate from the driving member and movable relative to the shaft cooperating with the shaft and driving member for establishing driving relation between the driving member and the shaft after such driving member has reached a positive limit in its longitudinal movement.

22. An engine starter apparatus including a shaft, a driving member movable longitudinally thereon for engagement with a member of the engine to be started, manually operated means for moving such driving member longitudinally into such engagement, and means separate from the driving member and controlled by the rotation of the shaft and adapted to establish driving relation between the driving member and the shaft after such engagement of the driving member with the engine member.

23. An engine starter apparatus including a rotatable shaft, a driving member mounted for longitudinal movement thereon into engagement with a member of the engine to be started and adapted to be rotatably connected therewith, manually operated means which is unconnected with such driving member but adapted to contact the same and so move it longitudinally into engagement, means movable to establish driving connections between the shaft and driving member after such longitudinal movement of the driving member, and means on the shaft for automatically disconnecting the driving member from the engine member when the engine operates under its own power.

24. An engine starter apparatus including a rotatable shaft, a driving member mounted for longitudinal movement thereon into engagement with a member of the engine to be started and adapted to be rotatably connected therewith, manually operated means having a member which is unconnected with such driving member but adapted to move the same longitudinally in one direction only, means for establishing driving connection between the shaft and driving member after such longitudinal movement, and means on the shaft for moving the driving member in the opposite direction to thereby disconnect the same from the engine member.

25. An engine starter apparatus including a rotatable shaft, a driving member mounted for longitudinal movement thereon into engagement with a member of the engine to be started and adapted to be rotatably connected therewith, said driving member being in the form of a pinion having a disk at its non-engaging end, manually operated means having a member adapted to contact the edge of such disk and to move the pinion longitudinally in one direction only and into engagement, means for establishing driving connection between the shaft and driving member after such longitudinal movement, and means on the shaft for automatically disconnecting the pinion from the engine member when the engine operates under its own power.
